(57) **CLAIM**

The ornamental design for a vacuum cleaner base portion, as shown and described.

DESCRIPTION

FIG. 1 is a front perspective view of a vacuum cleaner base portion which embodies our design;

FIG. 2 is a front view thereof;

FIG. 3 is a rear view thereof;

FIG. 4 is a right side view thereof;

FIG. 5 is a left side view thereof; and,

FIG. 6 is a top view thereof.

The material in dotted lines forms no part of our invention.
